UNITED STATES PATENT OFFICE

ROLAND L. McGEE, OF ST. PAUL, MINNESOTA

BOXING FIGURE TOY

Application filed July 20, 1927. Serial No. 207,048.

The present invention relates to a coin controlled amusement device.

An object of the present invention is to control the movements of a pair of figures to 5 simulate a boxing contest.

In order to attain this object there is provided, in accordance with one feature of the invention, a pair of figures mounted upon a supporting mechanism and having control 10 means mounted therein to control the movements of the figures.

These and other features of the invention will be more fully brought out in the following description and the accompanying drawings, wherein:

Figure 1, is a view in perspective of the device.

Figure 2, is a view in perspective of one of the figures and the supporting mechanism 20 therefor, portions thereof being broken away to disclose the structural features of the device.

Figure 3, is a view in longitudinal section through a controlling handle.

Figure 4, is a view in vertical section on the line 4—4 of Figure 3.

Figure 5, is a view in vertical section on the line 5—5 of Figure 3.

Figure 6, is a view in vertical section on the line 6—6 of Figure 3.

Figure 7, is a view in side elevation of a portion of the mechanism which controls the movement of the figure supported by the mechanism, the dotted lines showing the 35 position of the mechanism when the figure is in a prone position, the solid lines showing the position of the parts when the figure is restored to an upright position.

Referring to the drawings in detail, a casing 40 A is supported upon a standard B, said casing having an enclosed lower portion 1 with a floor 2 across the top of this enclosed lower portion. The upper portion 3 of the casing is enclosed by glass walls 4, which construction permits a free view of the interior 45 of this upper portion of the casing. A miniature boxing ring is provided by four upright corner posts 5 connected by cords 6. An opening is provided centrally of the ring thus formed, and over this opening, supported

above plates 7 and 8 are a pair of boxing figures 9 and 10. Each of the plates 7 and 8 is carried upon support members 11 and 12 which are firmly connected at their other ends to a handle member C. This handle member 55 is preferably shaped somewhat in the form of an automatic pistol. The method of mounting the figures is best shown in Figure 2. Since both figures are mounted and controlled in a similar manner the mounting and operating mechanism of but one of said figures will be described. A pivot pin 13 is connected transversely between the support members 11 and 12 and upon this support pin is pivotally mounted a bell crank lever 14 to the 60 upper arm 15 of which a foot of the figure is connected. The lower arm of the bell crank lever extends at approximately right angles to the upper arm 15 and is provided with a counter-weight 16 on the outer end thereof. 70 The counter-weight is sufficiently heavy to normally carry the figure backward to a prone position, as shown in dotted lines in Figure 7.

On either side of the bell crank lever 14 are arm controlling bell crank levers 17 and 18, 75 the downwardly extending arms of which are connected by operating wires 19 and 20 to manually actuated slide members 21 and 22. The horizontal arms of the bell crank levers 17 and 18 are connected to control the movements of the arms of the boxing figure, which arms are pivotally connected to the body of the figure. The bell crank lever 18 is connected by means of an actuating wire 23 extending upwardly through the hollowed leg 80 of the figure to an arm of a bell crank lever 24, the other arm of the bell crank lever 24, being connected by means of a link 25 to a lever arm 26 which is firmly secured to the pivotally mounted arm 27 of the figure. This 90 arm 27 of the figure is pivoted to swing in a horizontal plane. A second lever arm 28 is also firmly secured to the arm 27 of the figure and is connected to a spring 29 to normally retain the arm in a rearward position. The 95 other bell crank lever 17 is connected by means of an operating wire 30 to a bell crank lever 31, the other arm of which is connected by means of a link 32 to a lever arm 33, which is firmly secured to the arm 34 of the figure. 100

This arm 34 is pivoted to swing in a vertical plane, the weight of the arm being sufficient in this case to restore the arm to a normal position. Mounted within the chin of the boxer is a button or plunger 35 which is connected as by means of a stiff spring 36 to rest against an arm of a bell crank lever 37, the other arm of which is connected by means of a wire 38 to a bell crank lever 39 mounted in the forward foot of the figure. The spring 36 is not under compression since if it were it would hold the bell crank lever constantly in a released condition, but merely acts as a means to cushion the shock of a blow on the button 35 in transmitting it to the bell crank lever 37 to prevent injury thereto. The other arm of the bell crank lever 39 is hook-shaped to engage a hook 40 secured to the plate 7 to hold the figure in an upright position. Beneath the plate 7, a second plate 41 is mounted, having a recess 42 cut in the forward upper portion thereof. Within this recess, and mounted to slide freely between the plate 7 and the plate 42 is a third plate 43, being held in position therein by screws 44 riding in slots 45 in the slidably mounted third plate 43. Springs 46 are mounted to engage the rear edge of the slidable plate 43 to normally force it forward into abutment with a similar plate associated with the other boxing figure to close the gap between the floor plates 7 and 8 during manipulation of the boxing figures.

The handle member C is mounted in a ball joint 47, supported upon pivot screws 48 and 49 which are mounted in bearings 50 and 51 secured to the casing A. The handle member C is slidably mounted in a housing 52 integral with the ball joint 47, outwardly extending flanges 53 being provided on the inner end of the handle member to limit the rearward movement of the handle member.

The slide members 21 and 22 are mounted for free longitudinal sliding movement within the grip portion of the handle member, springs 54 and 55 being arranged rearwardly of these slide members to normally force them to a forward position. Extending through the forward end of the grip portion of the handle member are finger actuated portions 56 and 57, the forward ends of these portions being curved to the shape of a trigger to provide for easy manipulation of the slide members 21 and 22. Extending upwardly from the upper portions of each of the slide members are control wire support posts 57 and 58 to the upper end of each of which are connected the control wires which actuate the bell crank levers 17 and 18. These bell crank levers in turn control the movements of the arms of the boxing figures. The construction and arrangement of the slide members is best illustrated in Figure 4. The main body portion of the handle member C is constructed in two parts 59 and 60, in the grip portion of

which is an opening having ridges 61 and 62 extending longitudinally of the sides thereof. The slide member 22 is provided with longitudinal grooves therein, to receive the ridges 61 and 62. A portion of the slide member 22 is cut away to receive the second slide member 21 therein, a ridge 64 on the slide member 22 being arranged to ride in a groove in the second slide member to hold the parts in position. The slide members are thus firmly locked against lateral displacement, but are free to slide longitudinally of the handle member.

A plunger 65 is slidably mounted in the upper portion of the handle member, the inner end thereof being positioned between the two support members 11 and 12. The rearward end of the plunger is concave so as to permit the plunger to be pushed forward by the thumb or finger of the operator, a slot 66 (see Figure 1) being cut in the side of the handle member to accommodate the thumb or finger of the operator when the slide is pushed forward. The forward end of the plunger is reduced in thickness as at 67 and is arranged to engage the bell crank lever 14 upon which the boxing figure is mounted to restore it to an upright position after it has been dropped in manipulating the device.

The normal position of the plunger is shown in dotted lines in Figure 7, while the operated position of said plunger is shown in solid lines. The figure supporting bell crank lever is shown in solid lines in the position it occupies when the figure is in an upright position, and in dotted lines in the position it occupies when the figure is in a prone position. With the figure in a prone position the pushing of the plunger forward to the solid line position moves the bell crank lever 14 about its pivot and restores the figure to a vertical position.

A coin controlled mechanism is shown in Figure 3, although this forms no part of the present invention, since any suitable coin controlled mechanism may be employed. The coin controlled mechanism comprises a pawl 68 pivotally mounted in a recess above the plunger and normally held in the recess by the plunger 65. A coin opening 69 is provided in the plunger with a slot 70 above it for the insertion of a coin. When a coin 71 is inserted in the coin opening 69, upon moving the plunger 65 forward, the pawl 68 is moved up to the solid line position shown in Figure 3. By thus raising the pawl, which would otherwise engage the rear face of the coin opening 69 in the plunger and arrest the forward movement of the plunger, a full operative stroke of the plunger is permitted.

To operate the device, considering that one of the boxing figures is in a prone position, a coin 71 is inserted in the slot 70 of the control handle associated with the prone figure, and the plunger 65 is moved forward to

restore the figure to an upright position. A stud 72 projecting upwardly from the rear end of the plunger is engaged by a coil spring 73 to normally retain the plunger in a rearward position. The figures may then be manipulated by moving slide members 21 and 22 by means of the trigger extensions 56 and 57. The movement of the slide members, which in turn control the movements of the actuating wires 19 and 20, causes a lifelike manipulation of the arms of the fighters through the bell crank levers 17 and 18 and associated mechanism. The figures may be moved from side to side by turning the handle member 10 upon the pivoted ball joint 47, while forward and backward movement of the figures is accomplished by slidably moving the handle members C longitudinally of the supporting housing 52 of the ball joint 47. The object, 15 of course, is to strike the button in the chin of the opposing fighter which, when accomplished, moves the bell crank lever 37 about its pivot, and releases the hooked end of the bell crank lever 39 from the hook 40 connected 20 to the floor plate. The action of the counterweight 16 then drops the figure to a prone position, requiring the insertion of a coin and the operation of the plunger to restore the 25 figure to an upright position before it can be again manipulated.

The means of supporting and controlling the movements of the figures may be modified by one familiar with the art, and various types of coin controlled mechanisms may be 30 employed to restore the figures to a vertical position. These and similar modifications are intended to be included in the present invention, being limited only by the scope of the hereto appended claims.

40 I claim:

1. A boxing figure toy, comprising a frame, a pair of handle members movably mounted therein, a figure having movable arms carried on the inner end of each of said handle members, means selectively controlling the movements of the arms of said figure, said figure being releasably supported in an upright position, release means to move said figure to a horizontal position, and coin controlled means to restore said figure to a vertical position.

2. A boxing figure toy, comprising a frame, a support member movably connected thereto, an operating handle slidably mounted in said support member, a figure pivotally connected to the inner end of said handle, means to normally move said figure to a prone position, releasable means to hold said figure in an upright position, means mounted in the body of said figure and connected to said releasable means to release said figure to a prone position upon being struck, arms movably connected to the body of said figure, and manually controlled means operable from 65 said handle to control the movements of the

arms of said figure, said arms being movable to strike the means mounted in the body of an opposite figure and connected to the releasable means of said figure to release said figure for dropping to a prone position.

3. A boxing figure toy comprising a support member mounted for combined lateral and longitudinal movement, a grip portion on the outer end thereof to permit an operator to manually move said support member, a pair of triggers adjacent said grip portion positioned to be selectively operated by the operator holding said grip portion, a figure having movable arms mounted on the inner end of said support member, and control means interconnecting said arms and said triggers to control the movement of said arms by manipulation of said triggers.

4. A boxing figure toy comprising a support member movable in a horizontal plane, a pistol grip connected thereto to permit an operator to manually move said support member, trigger means adjacent said pistol grip to be operable by an operator holding said pistol grip, a boxing figure having movable arms carried by said support member, control means interconnecting said trigger means and said arms to selectively control the movement of said arms, means acting on said boxing figure to normally move it to a prone position, a coin released member having operative connection with said figure to move it to an upright position, latch means to hold the figure in an upright position, and means exposed on the body of the figure and having operative connection with said latch means to release said latch means upon a movement of said exposed means to drop the figure to a prone position.

In testimony whereof I affix my signature.

ROLAND L. McGEE.
